SEGMENTAL GRINDING WHEEL

George N. Jeppson, Worcester, Mass., assignor to
Norton Company, Worcester, Mass., a corpo-
ration of Massachusetts

Application June 13, 1935, Serial No. 26,338

8 Claims. (Cl. 51—206)

This invention relates to a grinding wheel, and more particularly to a segmental type of grinding wheel especially adapted for grinding logs into wood pulp.

In the production of wood pulp for paper manufacture, many unsuccessful attempts have been made to employ grinding wheels of the type commonly utilized in the metal industry, but such wheels have not proved satisfactory. A grinding wheel which is sufficiently large for efficiently grinding wood pulp presents difficult manufacturing problems, and the firing of such a large monolithic wheel usually results in its breakage or produces an abrasive body which is improperly annealed and very susceptible to breakage during use.

It is necessary to provide a very large and unusually strong abrasive wheel for pulp grinding since the logs which are ground to produce the wood pulp are large and heavy and the wheel must withstand enormous grinding forces. It is common practice to make pulpstones more than five feet in diameter and weighing as much as eight tons. The logs are forced against the operative face of such a stone under extremely heavy pressure, and under normal grinding conditions the pulpstone is rotated at approximately 250 revolutions per minute. In order to operate such a grinding wheel, as much as 1500 horse power is usually required.

In many wood pulp grinding operations, it is usual to maintain a relatively small amount of water within the grinding pit, hence the heavy friction of grinding frequently causes a rapid rise in temperature of the operative wheel face. Since many of these wheels are employed in cold climates, this variation may be from as low as zero degrees Fahrenheit to as high as that of the temperature of boiling water. Furthermore, the water in the grinding pit occasionally gets so low that it provides insufficient cooling for the wheel and at this time an operative wheel face has been known to rise to a temperature as high as 400° F. It is these sudden and excessive temperature changes which cause uneven expansions within these prior types of pulpstones and result in frequent breakage thereof. In view of the large size of pulpstones and their rapid rotational rate, breakage thereof often results in serious damage to the mill and subjects the machine operator to much danger.

In an endeavor to overcome these difficulties inherent in prior pulpstone constructions, it has been the more recent practice to provide wedge shaped arcuate wheel segments having reentrant

portions in their opposed radial side faces. As disclosed in the prior patents to Larsson et al., No. 1,736,161 of November 19, 1929 and No. 1,815,108 of July 21, 1931, which embody such a typical construction, a single wedge block is arranged to engage clamping faces within reentrant dovetailed portions of two adjacent segments and serves to simultaneously engage and secure both segments to a central iron drum. This method of fastening the segments to a central rotatable support has not been found entirely satisfactory due to the fact that it hinders uniform lateral expansion of the individual segments when subjected to sudden rises in temperature due to the friction of grinding. This impeding of uniform expansion of the segments may be sufficient to cause wheel breakage across the narrow throat of bonded abrasive material which extends between the reentrant dovetailed portions within the opposed faces of each segment. Furthermore, in view of the inherent fragility of the vitrified segments forming such a grinding wheel, many difficulties are encountered in this method of clamping the segments to a central support since they cannot be uniformly secured in grinding position.

As also shown in the noted patents to Larsson et al., the segments may be secured in spaced relation on their central support to aid in compensating for lateral expansions thereof occasioned by heat of grinding and, if desired, these spaces between the individual segments may be suitably filled with a deformable or compressible material. Grinding wheels of this general type have not only been expensive to produce, but have also presented many practical problems due to the internal stresses and strains set up within the individual segments during manufacture and later during their use in the grinding wheel. Pulpstones of this type have the further objectionable feature that in the event of breakage, the entire wheel must be removed from its mounting and returned to the manufacturer to be completely rebuilt since the segments within the wheel are not individually secured to their central hub. Unless the mill owner has gone to the heavy additional expense of providing a spare pulpstone to be used during such a contingency, breakage of a pulpstone necessitates a complete shut-down of the mill until the stone has been returned to the manufacturer, repaired and then sent back to the mill for use.

It is, therefore, the primary object of this invention to provide a segmental type of grinding

wheel wherein the segments may be uniformly and individually secured to a central support in such a manner that they are free to individually expand and contract under the influence of temperature changes and relieve internal wheel stresses during a grinding operation, thereby minimizing wheel breakage.

It is a further object of this invention to provide a segmental type of grinding wheel wherein the segments are individually and resiliently maintained in grinding position to compensate for expansions within the wheel during a grinding operation.

To the accomplishment of these objects and such others as will be apparent to one skilled in the art, I have provided a segmental grinding wheel especially adapted for producing wood pulp and composed of a plurality of bonded abrasive segments rigidly secured to a central rotatable support independently of each other and in such a manner that the segments may individually expand and relieve internal wheel stresses during grinding. The central rotatable support may be composed of any suitable moldable material which may be cast in position against the bottoms of the segments to form a supporting hub therefor. To correctly position and rigidly support the segments in proper cooperative grinding relation and provide a grinding wheel having a substantially continuous cylindrical grinding surface, each segment has one or more anchoring members such as nuts imbedded within its base portion and adjacent to the central wheel support. These anchoring members are in such spaced relation that they may aid in uniformly securing the segments in grinding position.

In order to secure each sector in grinding position under a desired clamping pressure, each anchoring member is connected to a suitable elongated tension member, such as a clamping bolt, which is slidably mounted within but adjustably secured under a predetermined initial tension to a sleeve member imbedded within and integrally secured to the central wheel support. These anchoring bolts preferably embody elastic properties, so that they may serve to resiliently secure the segments in grinding position on their central support under an initial predetermined but elastic tension to compensate for individual expansions of each wheel segment during a grinding operation. The segments are preferably mounted in spaced relation to each other and the crevices therebetween may be filled with various deformable or compressible materials which will adhere to the opposed faces of the adjacent segments and aid in compensating for lateral expansions of the individual segments towards each other as caused by the heat of a grinding operation.

The present invention is illustrated by the attached drawing wherein:

Fig. 1 is a fragmentary sectional view through a portion of my grinding wheel which illustrates my preferred type of segmental wheel construction;

Fig. 2 is a sectional view of a portion of my grinding wheel taken along the line 2—2 of Fig. 1; and

Fig. 3 is a sectional view showing a modified type of my grinding wheel construction.

In the preferred type of my invention, as illustrated in Figs. 1 and 2, I have provided a plurality of wheel sectors or segments 10 assembled

5 to form an integral grinding member, such as a pulpstone, of any desired size and having a cylindrical grinding face adapted to perform a heavy duty grinding operation, such as the grinding of logs into wood pulp. These segments are composed of abrasive grains, such as crystalline alumina, silicon carbide or other suitable granular abrasive material bonded together into the desired sector or wheel segment shape by a matured bond, such as a vitrified ceramic material of the 10 nature of porcelain or glass. The segments are provided with curved outer abrading faces 11 which cooperate with each other to form a substantially continuous peripheral grinding wheel face 13, opposed side faces 14, end faces 15, and 15 inner supporting faces 17 which are arranged to be seated on a rotatable central supporting member or hub 18, and preferably a monolithic center composed of concrete or other cementitious material which may be cast in position. The 20 abrasive segments are made as separate articles of manufacture independent of the central support 18 and they are so constructed that they may be individually and removably fastened to the central support by suitable anchoring devices without producing uneven stresses and strains within the segments during grinding or weakening their relatively fragile structure.

My preferred type of anchoring members, as 30 illustrated, may comprise nuts 21, each of which is imbedded within a cavity 22 cast or otherwise formed below the inner supporting face 17 and within the bottom portion of each segment. These nuts are rigidly and permanently secured 35 within the cavities in desired locations by Bab- bitt metal, Portland cement, sulphur or other suitable materials which may be cast in position around each nut to integrally secure it to the wheel segment. I preferably provide a sufficient 40 number of these imbedded nuts in such spaced relation to each other that each segment may be uniformly mounted on the central support 18 in desired grinding position. Each nut may be further provided with a knurled or otherwise roughened outer face 25 and the cavities 22 may be 45 provided with sharp reentrant portions, such as grooves 26, in the sides thereof which aid in rigidly and permanently locking the nuts in their required imbedded positions. As illustrated, one 50 or preferably several clamping members arranged in desired spaced relation may be employed to secure each segment individually to the central support 18.

Each wheel segment is supported in a pre-determined location upon a mating face 28 of the 55 monolithic central supporting member 18, and in my preferred construction these mating faces 17 and 28 of the segments and the central support are made flat to aid in uniformly supporting and rotating the segments during the grinding operation. If desired, the bottom face 17 of each segment may be coated with a thin sheet of paper, paint or other material to prevent the cementitious or moldable material of the support 18 from adhering to the segment. In order 60 to removably and individually secure the segments in position on the central support 18, the imbedded nuts 21 are secured under a predetermined tension to a central mandrel 31 coaxial with the grinding annulus by means of bolts 32 65 slidably mounted within metal sleeves 33 which are imbedded within the central support 18 and extend between nuts 21 and mandrel 31. If desired, the outer faces 34 of the metal sleeves 70 may be roughened to aid the material of the cen- 75

tral support 18 in positively gripping and firmly adhering thereto and making the embedded sleeves integral with the support. The upper ends of the bolts 32 are screw threaded into the imbedded nuts 21 and the lower ends of said bolts, which are also provided with screw threads, extend through holes 38 within the mandrel and have suitable clamping nuts 36 threaded thereon which engage the inner face of the mandrel and serve to provide the required tension on bolts 32 to locate the segments in position.

The metal sleeves 33 which surround the clamping bolts 32 serve the dual purpose of simplifying the wheel manufacture and wheel balance by co-axially locating the grinding annulus and mandrel, as well as relieving the central wheel support of any initial stresses and strains, usually caused by clamping devices. I preferably provide the bolts 32 with certain elastic properties which permit them to expand and contract within the sleeves 34 and thus compensate for expansions and contractions within the individual wheel segments during a grinding operation, as disclosed in the prior patent to Larsson et al., No. 1,736,161. I have thus provided a construction wherein my abrasive segments are not only removably clamped in position but also are so mounted that each of the clamping bolts may be maintained at an initial tension without exerting any clamping forces upon the central wheel support.

The sleeves 33, bolts 32 and anchoring nuts 21 are so positioned relative to each other and within the wheel that the abrasive segments are individually fastened to the central support in a predetermined spaced relation to each other with the opposed side and end faces of adjacent segments slightly separated from each other. The crevices thus formed between the adjacent segments may be filled with a compressible material such, for example, as a soft Babbitt metal, lead, zinc, a mixture of sulphur and ground coke commonly known by the trade name of "Lavasul", rubber or other suitable deformable materials which will aid in laterally supporting the segments and yet permit lateral expansions of the individual segments during grinding as caused by temperature changes within the wheel.

In assembling my preferred type of grinding wheel, as illustrated in Figs. 1 and 2, I cement a sheet of paper over the supporting face 17 of the segment or otherwise suitably coat the bottom face of the segment, as by paint, to fill the surface pores thereof and prevent the material of the central wheel support 18 from entering into the pore structure of the segment and from adhering thereto when the central support is cast in position. A clamping bolt 32 is then secured within each nut 21, thereby rigidly fastening one or more bolts to each wheel segment. A sleeve 33 is slid over each bolt and the inner ends of the bolts protruding from said sleeves are inserted through correspondingly located holes 38 within the central mandrel 31. A nut 36 is threaded on the inner end of each bolt and brought into engagement with the mandrel, as shown, to individually and removably clamp the segments in the form of an annulus and in desired spaced relation to each other. The nuts are preferably tightened against the mandrel sufficiently to stretch each bolt slightly but not beyond its elastic limit so that the sleeves will support the entire clamping force exerted by the bolts and the segments will be resiliently secured in position under a predetermined tension in such a manner that expansion of the wheel during grinding may be

compensated for by the elastic properties of the clamping bolts.

After the segments have been tightened in desired position, forming an abrasive annulus concentric with but radially spaced from the mandrel 31, the intervening space between the mandrel and the bottom of the segments is completely filled with a cementitious material, such as concrete or other suitable material which may be cast in position to form the central wheel support 18. To prevent the material 18 from entering within the crevices between the segments during the molding operation thereof, the bottom portions of said crevices adjacent to surfaces 17 may be filled with a moldable material, such as putty, or said crevices may be covered by strips of fibrous material, such as paper or cloth, stretched thereacross and secured to the surfaces 17 of adjacent segments. When the moldable material forming the central support has become set, the interstices between adjacent segment faces 14 and between segment faces 15 may be filled with a deformable material, such as Babbitt metal, lead, "Lavasul", rubber or other suitable compressible materials well known in the art.

The provision of a wheel construction of this type minimizes wheel breakage since any internal stresses within the segments will be compensated for in each segment by means of the clamping bolts 32 which are arranged to compensate for individual segment expansions. Hence, stresses and strains within the wheel during grinding will not tend to accumulate throughout the entire wheel and attain magnitude sufficient to cause wheel breakage. In other words, in a construction of this type, each segment is arranged to resiliently expand and contract by itself in grinding position and in the event that wheel breakage should occur due to improper wheel use, one or more segments may be individually replaced in the field without necessitating shipping of the entire grinding wheel back to the factory to be completely rebuilt, as has been necessary heretofore. In accomplishing a repair of this type, the broken segment may be removed by loosening nuts 36 securing it in position and breaking out the filling material 38 within the crevices between the segments. A new segment may then be inserted in the same position and secured under desired tension by means of nuts 36, after which the crevices between adjacent segments may be again filled with a suitable material, as heretofore described.

A modified form of my invention, as shown in Fig. 3 of the drawing, comprises a plurality of separately manufactured bonded abrasive segments 50 of the same general material, shape and size as the segments employed in my preferred type of invention. These segments are provided with arcuate outer grinding faces 51 which co-operate with each other in the assembled wheel to form an operative peripheral wheel face 53. As in my preferred type of invention, the segments are also provided with substantially radial opposed side faces, end faces 55 and inner supporting faces 57 which are arranged to be firmly seated upon a rotatable central support or hub 58 composed of a suitable cementitious material, such as concrete or other material which may be cast or molded in position against the bottom of the segments during wheel assembly to provide a rotatable support therefor.

Each of these abrasive segments is individually and permanently secured to the central wheel support 58 by one or more clamping devices 75

which are arranged to individually engage the segments under a predetermined initial tension without exerting any clamping forces upon the central wheel support itself. As illustrated, the 5 lower portion of each segment is provided with one or a plurality of spaced recessed or reentrant cavities 62 within which anchoring members such as nuts 63 are imbedded. These nuts are permanently and rigidly secured in position 10 within said cavities by a cementitious material 64, such as Babbitt metal, Portland cement, sulphur or other suitable materials which may be cast in position about each nut and fill the cavities. The nuts are preferably provided with 15 knurled outer faces 65 and the cavities are provided with grooves or reentrant portions 66 in their side faces to aid in securing the cement 64 and nuts 63 integrally to the segments. One or 20 preferably a plurality of these nuts are secured within the bottom of each segment in such spaced relation that each segment may be uniformly 25 secured in position upon the central rotatable support 59.

The segments are each secured in position with 25 their respective inner faces 57 seated upon correspondingly shaped faces 70 of the molded central support 59, and these mating faces are preferably made flat to evenly support the segments and aid in imparting rotation thereto. As in my 30 preferred construction, the bottom face of each segment may be coated with a thin sheet of paper or paint to prevent the cementitious material of the central support 59 from entering the segments and adhering thereto during wheel 35 assembly. To rigidly and permanently secure the segments in position, each imbedded nut 63 is engaged by an elongated clamping tension member, such as a bolt 74, threaded therein. A sleeve 75 is slidably mounted on each bolt and 40 clamped in position between nut 63 and a clamping nut 77 threaded upon the inner end of each bolt. Hence, it will be appreciated that each nut 77 may be so tightened against an end of sleeve 75 that each clamping bolt may be secured 45 to its segment under an initial predetermined clamping pressure. As in my preferred type of construction, these bolts 74 may be provided with certain elastic properties which compensate for wheel expansions during a grinding operation, 50 as described in the prior patent to Larsson et al. No. 1,736,161. A portion of each clamping device including sleeves 75, nuts 77 and the protruding ends of bolts 74 are imbedded within the cementitious central support 59 which firmly adheres thereto and serves to hold the segments in 55 position.

If desired, the outer face of sleeves 75 may be roughened or provided with knurled portions to aid the cementitious material of the central support in securing them in position as integral members therewith. Hence, any expansive forces within the grinding wheel during grinding operations, such as those normally caused by the heat of grinding, may be compensated 60 by the elastic properties of bolts 74 which are free to expand and contract within the sleeves 75. The sleeves are made of suitable length and the bolts may be provided with such elastic properties as are necessary to meet the requirements 65 of each individual wheel. In a construction of this type, each segment will be individually clamped in position under an initial tension which may be regulated prior to wheel assembly, but this tension is resisted entirely by the sleeves 70 75 and is not transmitted to the central wheel

support 59, as is the case in prior segmental grinding wheel constructions employing segments clamped to a central support. If desired, the segments may be located in spaced relation during assembly and, as in my preferred type of invention, the spaces between the adjacent segment faces may be filled with a suitable deformable material to further aid in compensating for lateral expansions of the segments. 5

In the manufacture of this modified type of 10 my invention, the nuts 63 are suitably secured within the cavities 62 by means of cementitious material and bolts 74 are firmly screw threaded into the nuts. A sleeve is slid over each of the bolts 74 and a nut 77 is threaded on the protruding end of each bolt and thereafter tightened against the sleeve under a predetermined initial tension. It will thus be noted that each bolt 74 is secured under a predetermined initial tension before assembly of the grinding wheel. 15 The segments are then mounted by means of suitable clamps or guides in the form of an annulus and the cementitious wheel support 59 is cast against the bottom faces 51 of each segment and around the sleeves 75 and nuts 77, thereby forming 20 an integral grinding unit. If desired, the segments may be mounted in spaced relation to each other and a suitable deformable material cast in the crevices therebetween, as described 25 in my preferred type of invention. 30

Having thus described my invention, what I claim as new and desire to secure by Letters Patent is:

1. A grinding member comprising a bonded abrasive block, a support therefor composed of a 35 material molded in situ, an anchoring device including an elongated elastic tension member arranged to secure the abrasive block upon the support, and means embedded within the support which maintains the tension member under 40 an initial predetermined tension, thereby resiliently fastening the abrasive block upon its support and compensating for expansion and contraction within the grinding member.

2. A grinding wheel comprising a plurality of 45 bonded abrasive segments arranged in the form of an annulus, a rotatable central support therefor composed of a material cast in position against the bottoms of the segments, an anchoring device securing each segment upon the support including an elongated elastic tension member, and means embedded within the support 50 which secures the tension member thereto and permits free expansive and contractive movement thereof. 55

3. A grinding wheel comprising a plurality of bonded abrasive segments arranged in the form of an annulus having a peripheral grinding face, a rotatable central support therefor composed of a material cast in position against the abrasive 60 annulus, anchoring devices fastening the segments upon the support, each of said devices including an elongated elastic tension member connectible with a segment, a member embedded within the support which secures the tension 65 member in position but permits slideable movement thereof, and means engageable with the embedded member for securing the tension member under an initial tension, thereby resiliently fastening each segment in grinding position and 70 compensating for expansions within the wheel during grinding.

4. A grinding wheel comprising a plurality of bonded abrasive segments, a rotatable hollow central support therefor composed of a material 75

5 molded in situ, anchoring devices securing the segments upon the support, each of said devices including a sleeve member embedded within the support, an elastic tension member movable within each sleeve, means at one end of each tension member integrally securing it to a segment and means at the other end of each tension member arranged to individually and removably secure the segments in position under a predetermined 10 but resilient tension to compensate for wheel expansions during grinding.

10 5. A grinding wheel comprising a plurality of spaced bonded abrasive segments arranged in the form of an abrasive annulus having a substantially continuous grinding face, a rotatable central support therefor composed of a material molded in position against the bottom of the segments, an anchoring device individually and resiliently fastening each segment upon the support in grinding position which includes an elongated elastic tension member arranged to compensate for expansion and contraction within the wheel, means at one end of said member embedded within the bottom of a segment and integrally 20 secured thereto, and means embedded within the support and engageable with said tension member which permits free expansive and contractive movement thereof and serves to maintain said member under an initial predetermined tension so that the segments may be individually and resiliently secured in position under a predetermined tension.

20 6. A grinding wheel comprising a plurality of bonded abrasive segments arranged as an abrasive annulus, a rotatable central support therefor, anchoring devices securing the segments to the support including elongated elastic tension members which compensate for expansions and contractions within the wheel during grinding and means to exert a predetermined initial tension upon each tension member without exerting any clamping force between the segments and their support.

30 40 7. A grinding wheel comprising a plurality of

bonded abrasive segments arranged in the form of an abrasive annulus, a rotatable central support therefor composed of a cementitious material cast in position against the bottom of the segments, an anchoring device individually securing each segment to the support including an elongated elastic bolt arranged to expand and contract during grinding and compensate for expansive stresses and strains within the wheel, a sleeve member integrally secured to and embedded within the support which permits a relative slidable movement of the bolt therein, means removably engageable with one end of the bolt embedded within a segment, and means removably engageable with the other end of said bolt and engageable with said sleeve to resiliently secure each segment in position under a predetermined tension.

8. A grinding wheel comprising a plurality of separately manufactured bonded abrasive segments assembled as an annulus having a cylindrical grinding face, a rotatable central support therefor composed of a material cast in position against the bottoms of the segments, a plurality of spaced anchoring devices arranged to individually and removably secure each segment upon its central support, each anchoring device including an elongated elastic tension bolt arranged to compensate for individual expansions of the segments during grinding, anchoring members embedded within the bottom portion of each segment and removably engageable with said elastic bolts, a rigid sleeve member embedded within and integral with the support, each sleeve engaging an anchoring member and permitting slidable movement of an elastic bolt therein, and means adjustably and removably engageable with an elastic bolt and sleeve which maintains said bolt under an initial predetermined tension and resiliently but removably secures each segment in position in such a manner that it may be replaced irrespective of other segments in the wheel.

GEORGE N. JEPSON.
